Patented Sept. 7, 1920.

Fig:1.

UNITED STATES PATENT OFFICE.

LEOPOLD BACHRACH, OF NEW YORK, N. Y.

CARD-INDEX DIRECTORY.

1,351,730.

Specification of Letters Patent. Patented Sept. 7, 1920.

Application filed December 23, 1919. Serial No. 346,996.

To all whom it may concern:

Be it known that I, LEOPOLD BACHRACH, a citizen of the United States, and resident of the borough of Manhattan, in the city, 5 county, and State of New York, have invented certain new and useful Improvements in Card-Index Directories, of which the following is a specification.

The present invention relates to improvements in card index directories, particularly for attachment to telephones, and adapted to contain in alphabetical arrangement the names, exchanges, and numbers of certain selected subscribers, which the user 10 wishes to have before him without the necessity of consulting the telephone directory book. The object of the invention is to provide such a device which will be of simple and compact construction, may be attached 15 to the telephone with facility and in a manner as not to interfere with its operation, and with which the desired number may be found readily. To this end, I propose to provide a plurality of indexed cards sus- 20 pended upon rings and adapted to be swung about said rings to expose the desired card, the cards normally in front of this card being swung about the rings to the rear of the 25 group of cards. I further propose to provide novel means for conveniently returning all of the cards to initial or normal position, that is, with a protective cover card, 30 or with the first or "A" card to the front. A further object is to provide such means by 35 which the exposed card may be inclined so as to better meet the line of vision of the user, and thereby enable him to give the operator the number with assurance, having the number directly before him as he is talk- 40 ing. I further propose to enable the cards to be readily removed, replaced and added to, to the end that the names may be type- 45 written on the cards when removed, and may be kept up-to-date and corrected as desired.

It is a further object of my invention to provide a form of construction which will eliminate to a great extent wear upon the cards and which will always maintain them 50 in superimposed alined position relatively to each other, so that the device always presents a neat appearance.

With these and other objects in view, an embodiment of my invention is shown in the accompanying drawings, and this embodiment will be hereinafter more fully de-

scribed with reference thereto, and the invention will be finally pointed out in the claims.

In the accompanying drawings, Figure 1 is 60 a front elevation of a telephone, showing one embodiment of my invention attached thereto.

Fig. 2 is a side view of the device.

Fig. 3 is a front elevation of the device 65 and showing one of the cards exposed.

Fig. 4 is a side view of the device in the position illustrated in Fig. 3, and showing in dotted lines the manner of inclining the exposed card to be better observed. 70

Fig. 5 is a vertical longitudinal sectional view of the supporting means for the cards, with parts broken away.

Fig. 6 is a sectional view of the supporting means taken along the line 6—6 of 75 Fig. 5.

Fig. 7 is a front elevation of a modified form of construction.

Fig. 8 is a side view thereof with a portion broken away. 80

Similar reference characters indicate corresponding parts throughout the several figures of the drawings.

Referring to the drawings, the embodiment of my invention shown therein comprises a clamp adapted to be secured to the post 10 of the telephone instrument, and consisting of a pair of semi-circular strap members 11 and 12 provided with lugs 13 and 14, having screws 15 and 16 secured therethrough to tighten the same in engagement with the telephone post, one of the lugs 14 being extended laterally as at 17, and having secured thereto by a rivet 17^a or other suitable means, a laterally extending shaft or rod 18, screw-threaded at its outer end, and provided with a nut 19 screwed thereon, and constituting with the end of the portion 17 limiting abutments for a sleeve 20 rotatably mounted on the said 100 rod 18.

At the ends of the sleeve there are provided upon slightly reduced portions 21 and 22 thereof, pairs of concavo-convex disks or washers 23, 24, and 25, 26, having their concave sides faced to each other and tightly clamped against the shoulders formed by the reduced end portions by upsetting the ends of the sleeve as at 27 and 28. 105

Between the disks 23 and 24 there is 110 clamped the hooked end 29 of a U-shaped frame 30, the hook extending over the re-

duced portion 21 of the sleeve to hold the frame securely to the sleeve, while registering cut-outs 31 and 32 are provided in the peripheries of the disks embracing the frame 5 to prevent turning movement thereof relatively to the disks, and at the same time permit the peripheries of the disk to fit snugly against each other.

Between the disks 25 and 26 there is 10 clamped the other end of the frame, the same being extended above the disks however, and bent outwardly as at 33 to form a handle, a rotatable knob 34 being provided thereon. This end of the frame is made 15 secure to the disks and sleeve by means of a humped portion 35 embracing the sleeve, and diametrically opposite pairs of registering cut-outs 36, 37, and 38, 39, in the peripheries of the disk. 20 The lower end of the frame 30 is provided with an upwardly bent reentrant portion 40 of inverted V shape and bent slightly forwardly, so that its apex engages the index cards, constituting a lifting or supporting finger, as will presently more fully appear. 25

Upon the sleeve between the disks, which constitute end flanges, there are disposed a pair of split rings 41, 42, which may be of 30 any suitable type to enable the engagement of loose cards therewith. A plurality of index cards 43, perforated as at 44, 45, to engage the rings 41 and 42, are supported within the frame, their lower ends being 35 relatively near the lower end of the U frame, and below the upper end of the finger portion 40. The cards are provided at one side edge with lettered index tabs 46, offset relatively to each other, so that they are all 40 exposed to view, the cards being suitably ruled preferably at both sides and designated to receive names and numbers as desired.

The "A" or first index card is preferably 45 the second card of the group, the first card being of heavier or more durable material and being in the nature of a cover or protective card. It may, if desired, contain advertising matter. The disks at the ends of 50 the sleeve constitute abutments to limit the side movement of the cards, so that their edges will not come into contact with the sides of the frame 13.

When it is desired to ascertain a number, 55 the desired card is selected by means of the index tabs, and the cards forwardly of the same are swung about the rings 41, 42, to the rear of the frame, as indicated in Figs. 3 and 4. The frame may, if desired, be 60 tilted upwardly into inclined position by means of the handle, as shown in dotted lines in Fig. 4, in order to bring the exposed card substantially at right angles to the line of vision of the user, and thereby make the 65 reading of the number while using the tele-

phone more convenient. When the desired number has been found, the cards may be returned to normal position with the cover or protective card foremost by swinging the frame forwardly in the direction of the arrow, Fig. 4, through a complete circle, thereby placing all of the cards forwardly of the frame. This operation is extremely simple, and inasmuch as the cards need not be handled, they will be less subject to wear and 70 otherwise. The split rings enable the cards to be conveniently removed and replaced.

In Figs. 7 and 8 I have illustrated a modified form of construction, and in which form the device is adapted for more general use 80 as an index, although it will be understood that in this form it may be placed in proximity to a telephone and be used as a telephone index, or the modified features other than the supporting frame may be incorporated if desired in the form of device where it is attached directly upon a telephone. Referring to these figures the shaft 47 is mounted at its ends in bearings 48 and 49 provided at the upper end of a supporting frame 85 structure having a relatively wide and heavy base portion 50 and inverted V shaped side portions 51 and 52, the base being of such dimension and weight as to prevent the device from being easily toppled over. Upon 90 the shaft 47 there is rotatably mounted a sleeve 53 having rigidly connected thereto at its ends a frame 54 in a similar manner to the connection of the frame 30 in the form of the device shown in Figs. 1 to 6, the handle 100 55, however, being in the form of a knob having its longitudinal axis in line with the axis of the side portion of the frame, so that the frame may be completely swung around without interference of the knob with the 105 side portion 52 of the supporting frame.

At each side of the center of the sleeve 53 there are provided pairs of spaced flanges 56 between which there are mounted split rings 57 and 58 removably engaged in the 110 perforations 59 and 60 of the cards 70. The flanges 56, it will be noted, prevent lateral movement of the rings and in order to prevent lateral swinging movement of the cards 115 so that they will be held out of contact with the frame 54 at its sides, there is provided centrally of the sleeve 53 a rigid flange or washer 61 of circular form engaging notches 62 provided in the upper edge of the cards.

At the lower end of the frame 54 there is 120 provided an upwardly bent reentrant portion 63 of inverted V shape engaging the cards at the rear and constituting a lifting or supporting finger. The finger 63 is first bent upwardly as at 64 in the plane of the 125 frame 54, rearwardly and inclined downwardly slightly therefrom as at 65 to form a shelf upon which the lower ends of the cards may be supported and upwardly as at 66 to engage the cards at their rear side. 130

By thus supporting the cards the weight of the same is normally removed from the rings so that wear upon the same at their perforated portions is relieved to a great extent. 5 Inasmuch as the cards are restricted against lateral movement, the corners and the lettered tabs will not come in contact with the frame 54 and will therefore be protected against damage by such contact with the 10 frame.

The device according to my invention is simple and inexpensive in construction, easy to attach to a telephone, is compact and inconspicuous, will not interfere with the 15 operation of the telephone and is efficient and practical in use.

I have illustrated and described a preferred and satisfactory embodiment of my 20 invention, but it is obvious that changes may be made therein within the spirit and scope thereof, as defined in the appended claims.

I claim:

1. An index device comprising a shaft support, a frame rotatably mounted on said 25 shaft support, a plurality of index cards suspended within said frame and engaged at their rear by said frame, said cards adapted to be individually swung about said shaft to bring the cards normally forwardly 30 of the card to be exposed rearwardly of said frame, said frame adapted upon being rotated in one direction about said shaft to place all of the cards forwardly thereof.

2. An index device comprising a shaft support, a frame rotatably mounted on said 35 shaft support, a plurality of index cards suspended within said frame and engaged at their rear by said frame, said cards adapted to be individually swung about said shaft support to bring the cards normally forwardly of the card to be exposed rearwardly of said frame, a handle on said 40 frame for rotating the same, said frame adapted upon rotation in one direction to place all the cards forwardly thereof.

3. An index device comprising a shaft support, a frame rotatably mounted on said 50 shaft support, a plurality of index cards suspended within said frame, said frame being provided with a finger portion engaging the rear of said cards, said cards adapted to be 55 individually swung about said shaft support to bring the cards normally forwardly of the card to be exposed rearwardly of said frame, said frame adapted upon being rotated in one direction about said shaft to place all the cards forwardly thereof.

4. An index device comprising a shaft

support, a sleeve rotatably mounted on said support, a frame rigidly connected to said 60 sleeve, said sleeve and frame adapted to be rotated about said shaft support, a plurality of index cards suspended within said frame, and engaged at their rear by said frame, said cards adapted to be individually swung 65 about said shaft to bring the cards normally forwardly of the card to be exposed rearwardly of said frame, said frame adapted upon being rotated in one direction about said shaft to place all of the cards forwardly thereof.

5. In combination with a telephone instrument, an index device comprising a clamp secured to said instrument, a laterally extending shaft supported by said clamp, a 75 frame rotatably mounted on said shaft, a plurality of index cards suspended vertically within said frame and engaged at their rear by said frame, said cards adapted to be individually swung about said shaft to 80 bring the cards normally forwardly of the card to be exposed rearwardly of said frame, said frame adapted upon being rotated in one direction about said shaft to place all the cards forwardly thereof.

6. An index device comprising a shaft support, a frame rotatably mounted on said shaft support, a plurality of index cards suspended within said frame and engaged at their rear by said frame, said cards 90 adapted to be individually swung about said shaft to bring the cards normally forwardly of the card to be exposed rearwardly of said frame, said frame adapted upon being rotated in one direction about 95 said shaft to place all of the cards forwardly thereof, and means for preventing lateral movement of said cards within said frame.

7. An index device comprising a shaft 100 support, a frame rotatably mounted on said shaft support, a plurality of index cards suspended within said frame, said frame being provided with a finger portion engaging the rear of said cards, said finger portion having a part bent to engage the lower ends of said cards, said cards adapted to be 105 individually swung about said shaft support to bring the cards normally forwardly of the card to be exposed rearwardly of said frame, said frame adapted upon being rotated in one direction about said shaft to place all the cards forwardly thereof.

In testimony that I claim the foregoing as my invention I have signed my name.

LEOPOLD BACHRACH.
